AIR CONDITIONING APPARATUS

Clifford S. Cody and Regis D. Heitchue, Springfield, Mass., assignors to Westinghouse Electric & Manufacturing Company, East Pittsburgh, Pa., a corporation of Pennsylvania

Application February 3, 1940, Serial No. 317,094

3 Claims. (Cl. 62—140)

Our invention relates to air conditioning apparatus, more particularly to a self-contained unit air cooler, such as one that may be mounted in a window of a room to be cooled.

An object of the invention is to provide improved apparatus of the character set forth.

A more particular object is to provide a unit air cooler of simple construction, whereby the same may be manufactured at low cost.

A further object is to provide an air cooler comprising a refrigerating unit and an improved structure for mounting the unit in a window, a more particular object being to prevent removal of the mounting structure from the window until the refrigerating unit has been withdrawn therefrom.

These and other objects are effected by our invention as will be apparent from the following description and claims taken in connection with the accompanying drawings, forming a part of this application, in which:

Fig. 1 is a side elevational view, partly in section, of our new unit air cooler mounted in a window;

Fig. 2 is a vertical sectional view, taken along the line II—II of Fig. 3, of the refrigerating unit removed from the mounting structure;

Fig. 3 is a plan view of the refrigerating unit;

Fig. 4 is a front elevational view of the refrigerating unit disposed in the mounting structure;

Fig. 5 is an elevational view showing the relation of the condenser fan to the condensate pan.

Fig. 6 is a fragmentary view, in vertical section, showing the rubber mounting of the unit; and,

Fig. 7 is a perspective view of the combined base and condensate pan with the partition mounted thereon.

Referring to the drawings in detail, our invention comprises a unit air cooler 10 adapted to be mounted, as shown in Fig. 1, in the window of the room to be cooled. It extends horizontally, the front portion projecting into the room and the rear portion projecting exteriorly of the room.

The air cooler includes a refrigerating system which is incorporated in a refrigerating unit 11, shown by itself in Figs. 2 and 3. The refrigerating unit is inserted horizontally in a mounting structure 12, shown in Figs. 1 and 4, which also forms a casing therefor.

The refrigerating unit 11 comprises a base member 13, shown particularly in Fig. 7. In accordance with our invention, this base member

is formed, as shown on the drawings, so as to serve as a condensate drain pan. For this purpose, it is formed with an upstanding flange 14 extending about the periphery thereof. It is made corrosion-resistant in any suitable manner, as by painting the same with an asphalt paint. The base member thus serves two purposes, namely, to support the entire refrigerating system which cools the air and also to retain the moisture condensed from the air by the evaporator. Accordingly, the need for a separate drain pan is dispensed with.

An upstanding partition 15 is secured to the base member 13, as shown particularly in Fig. 7, and forms a division between an evaporator compartment 16 and a machine compartment 17, formed by the base member 13 and the mounting structure 12. The partition 15 may include a portion 5 formed as a housing for electrical equipment, such as the capacitor for the compressor motor. As shown in Fig. 2, a gasket 6, of suitable form and suitable material such as rubber, is preferably attached to flanges formed along the top and side edges of the partition 15. This gasket serves to engage the hereinafter-mentioned walls of the mounting structure 12 and forms an air seal between the compartments 13 and 17. Heat insulating material 7 is preferably attached to the partition 15 to minimize flow of heat from the machine compartment 17 to the evaporator compartment 16.

The refrigerating system includes an evaporator 18, which may be of any suitable form, such as the cross-finned coil shown on the drawings, and which is disposed in the evaporator compartment 16 along the front thereof. The evaporator is mounted on the base member 13 in a suitable manner; for example, it may be provided with end plates 19 having flanges at their lower ends secured by screws to raised or embossed portions of the base member, as shown at 20. The system further includes a motor compressor unit 21, which is preferably of the enclosed type, comprising a compressor, a motor 45 for driving the same, and a fluid-tight casing enclosing both the compressor and the motor. It is disposed in the machine compartment 17 and resiliently mounted on the base 13 by means of three resilient mountings 22, which may be 50 of any suitable type known in the art, comprising either springs, rubber, or other resilient means. The condenser 23 may also be of the cross-finned type and is disposed in the machine compartment 17 along the back. It is mounted on the base member 13 in a suitable manner;

for example, end plates or brackets 24 may be provided at its ends and secured to the flange 13 by screws 25, as shown in Fig. 3.

The refrigerating system further includes parts for connecting the evaporator, the motor compressor unit, and the condenser in a complete refrigerating circuit through which the refrigerant is circulated. Such parts include a capillary tube 21 for conveying condensed refrigerant from the condenser to the evaporator and for reducing the pressure thereof, a suction conduit 28 for conveying the vaporized refrigerant from the evaporator to the motor compressor unit, a separating chamber or reservoir 29 interposed in the suction line 28 to retain any liquid refrigerant leaving the evaporator, thereby preventing its admission to the motor compressor unit, and a discharge conduit 31 for conveying the compressed refrigerant from the motor compressor unit to the condenser. Preferably, the capillary tube 21 and the suction conduit 28 are soldered to each other, as shown particularly in Fig. 3, thereby providing a heat exchanger for transferring heat from the refrigerant in the capillary tube to the refrigerant vapor in the suction conduit 28. The capillary tube and the suction conduit extend through a notch 32 formed in the upper portion of the partition 15.

Propeller fans 33 and 34 are provided for effecting flow of air through the evaporator and the condenser, respectively. They are overhung on the shaft of an electric motor 35 disposed in the machine compartment on the left-hand side of the unit, as shown in Figs. 3 and 4, with the shaft extending horizontally from front to back and with the front end of the shaft projecting into the evaporator compartment 16 through an opening 36 in the partition 15. The fan 33 is disposed adjacent the left-hand portion of the evaporator coil and is surrounded by a fan shroud 37 carried by the evaporator coil 21. The fan 33 is effective to draw air from the room into the evaporator compartment through the right-hand portion of the evaporator and then to discharge the same into the room through the left-hand portion of the evaporator.

The condenser fan 34 is similarly arranged adjacent the left-hand portion of the condenser 23. It is disposed in a fan shroud 38 carried by the condenser 23. The fan 34 is effective to induce flow of air from outdoors into the machine compartment through the right-hand portion of the condenser 23 and to discharge the air back to outdoors through the left-hand portion of the condenser.

The base member 12 is formed with an opening 41, shown in Fig. 2, disposed in that portion of the base which projects exteriorly of the window opening. A sheet metal conduit member 42 cooperates with the base member to form a passage 43 extending from the opening 41 to an opening 44 formed in the member 42 and communicating with the evaporator compartment 16. A hinged door 45 is adapted to control the admission of outdoor air through the opening 44, and is actuated in any suitable manner, as by means of a chain 46 extending to the exterior of the unit. The duct member 42 is also utilized to support the fan motor 35 thereon.

The mounting structure 12, shown in Figs. 1 and 4, comprises a top wall 47 and opposite side walls 48, which are preferably of sheet metal and close the top and sides of both the evaporator compartment 16 and the machine compartment 17. Angle irons 49 extend from the front to the

back along the lower edges of the side walls 48 and provide horizontal flanges 50 on which the unit 11 is supported. The bottom of the compartments 16 and 17 is closed by the base member 13. However, wall portions may be provided across a portion of the bottom of the structure 12 to connect the lower edges of the side walls 48; sufficient opening being left, however, to provide flow of air through the opening 41. The front and back of the structure 12 are open to provide for flow of room air and outdoor air, respectively.

To fasten it in the window, the mounting structure 12 is provided with a flange 51 adapted to engage the outer edge of the window sill 52 and with clamp members 53 adapted to engage the inner edge of the window sill. Each clamp member 53 is provided with an elongated slot 54, and screws 55 extend through openings in the flanges 50, the slot 54 and through screwthreaded openings in a block 56. A plurality of washers 57 are provided between the outer end of the clamp member 53 and the flange 50. Thus, by turning the screws 55, the clamp members 53 may be pulled upwardly to clamp the inner edge of the window sill. The slots 54 are elongated to permit adjustment of the clamp members 53 to window sills of different widths. It will be noted from Fig. 1 that the heads of the screws are disposed on the upper or inner side of the flange 50, so that it is not possible to turn the screws from the outside of the mounting structure.

The fastening means for the mounting structure 12 further includes a flange 58 at the top thereof adapted to engage the inner side of the window sash 59. Clamp members 60 are adapted to engage the outer side of the sash. The lower end of each clamp member is inserted in either one of two openings 61, formed in a plate 62 spot-welded to the top wall 47, and is of reduced width to form shoulders engaging the upper surface of the plate 62. The clamp member extends through and is longitudinally slid able in a slide member 63. A screw 64, whose head is disposed in a recessed portion of the plate 62, as shown in Fig. 1, and engages the lower or inside surface of the plate, is screw-threaded in the slide member 63. The clamp member is formed with a suitable slot to accommodate the screw 64. Since the head of the screw 64 is disposed interiorly of the mounting structure, the unit 11 must be withdrawn to obtain access thereto. By turning the screw 64, the clamp member 60 may be pulled down to clamp the sash 59 between the same and the flange 58.

It will be apparent, therefore, that as long as the unit 11 is disposed within the mounting structure 12, access to the heads of the screws 55 and 64 cannot be had, so that it is impossible to unfasten the mounting structure from the window. To remove the same, it is necessary first to remove the unit 11, thereby eliminating the danger which would accompany unfastening of the mounting structure from the window with the unit disposed therein.

The flanges and the clamp members just described are disposed, as shown in Fig. 1, to hold the mounting structure 12 in such position that the top and bottom thereof, and particularly the flanges 50, slope downwardly toward the exterior. Since the base member 13 rests on the flanges 50, it also slopes downwardly toward the exterior or outdoor side of the unit. This arrangement assures that the condensate collected by the evaporator will always flow toward the outside of the

room, so that the condensate can never overflow within the room.

Suitable provision may be made for excluding rain water from the room; for example, the flanges 51 and 58 may be provided with suitable gaskets. Any suitable provision may be made, when necessary, for closing the space between the sides of the mounting structure and the sides of the window opening.

As a further means of providing quiet operation, the unit 11 is resiliently mounted on the flanges 50 of the mounting structure. Such resilient mountings comprise blocks of rubber 65 having upper and lower face plates 66 and are attached to the underside of the base member 13 by means of screws 67. As shown in Fig. 6, the base member is formed with raised portions 68 forming recesses to receive the resilient mountings. These recesses reduce the height of the unit to the extent of the space that would otherwise exist between the base member and the flanges.

A wood outer cabinet 11 is preferably provided for the front portion of the air cooler which projects inwardly from the window. It is provided with louvers 72 in the front, as shown in Fig. 1. An air filter 13 is disposed across the front of the evaporator and filters the room air before and after it passes over the evaporator. It also filters the fresh air which is admitted through the passage 43 and discharged with the room air. This filter may be carried by the wood cabinet, being held between the top wall and the bottom flange thereof as shown in Fig. 1.

Operation

The refrigerating system operates in the usual manner of such apparatus. Refrigerant vapor is compressed by the motor compressor unit 21 and circulated through the refrigerant circuit. It is condensed in the condenser 23, its pressure is reduced by the capillary tube 27, and it is vaporized in the evaporator 18, thereby extracting heat from the air circulated over the outer surfaces of the evaporator by the fan 33.

The motor 35 is energized to drive the fans 33 and 34. The fan 33 circulates room air over the evaporator 18 and the fan 34 circulates outdoor air over the condenser 23, as described above. If the door 45 is open, the fan 33 is also effective to draw outdoor air through the passage 43 and to discharge the same into the room through the left-hand portion of the evaporator 21 and the filter 13.

The evaporator 18 cools the air flowing over the same to a temperature below the dew-point, thereby condensing moisture from the air. The condensed moisture is collected by the base member 13, which serves as a drain pan. The condensate flows to the outer side of the base member through an opening 14, formed below the partition 15 between the raised portion 67 and the conduit member 42. This moisture then collects in the rear portion of the base member 13, including the portion under the condenser fan 34. The latter is preferably disposed, as shown in Fig. 5, so that the tips of the blades in the lowermost position are disposed about $\frac{1}{8}$ inch from the upper surface of the base member 13. It has been found that, when the fan 34 is so disposed, the condensate is effectively evaporated.

From the above description and drawings, it

will be seen that we have provided relatively simple unit air cooler having a compact arrangement of parts.

While we have shown our invention in but one form, it will be obvious to those skilled in the art that it is not so limited, but is susceptible of various changes and modifications without departing from the spirit thereof, and we desire, therefore, that only such limitations shall be placed thereupon as are specifically set forth in the appended claims.

What we claim is:

1. In a self-contained unit air cooler, adapted to be mounted in a window of an enclosure to be cooled, the combination of a window mounting structure having means for mounting the same in a window, a self-contained cooling unit comprising a generally flat member forming a base for the unit and being formed with an upstanding flange so as to form a condensate pan, an evaporator and an air cooled condenser mounted on the portions of said base member projecting inwardly and outwardly, respectively, said mounting structure being adapted to receive and retain said unit in the window opening, said base member and the portions of said mounting structure on which the unit is retained sloping downwardly toward the exterior, so that condensate in said pan can never overflow inside the enclosure.

2. A structure for mounting a refrigerating unit in the window of an enclosure to be air cooled and formed to encompass said unit, said mounting structure including flanges on the top and bottom thereof for engaging the inner side 35 of the window sash and the outer edge of the window sill, respectively, clamp members on the top and bottom thereof for engaging the outer side of the window sash and the inner edge of the window sill, respectively, and screws extending through the top and bottom from the inside thereof and engaging said clamp members, said screws having heads on the interior of the mounting structure and the construction and arrangement of parts such that said unit must be withdrawn from the mounting structure to obtain access to the heads of said screws for disengaging them from said clamp members.

3. A window-mounted self-contained unit air cooler comprising bottom, top, and vertical walls forming an enclosure for the unit, means for mounting the unit air cooler in the window of a room, an upstanding partition within the enclosure dividing the same into an air cooling compartment and a machine compartment, an evaporator in the air cooling compartment, a compressor and a condenser in the machine compartment, means for connecting said evaporator, said compressor and said condenser in a complete refrigerant circuit, said bottom wall having an outdoor air inlet therein disposed at least partly on the machine compartment side of the partition, a duct member in the machine compartment providing a passage extending from said inlet opening to and communicating with the air cooling compartment, a fan motor mounted on said duct member, and a fan driven by said fan motor for effecting flow of outdoor air over said condenser.

CLIFFORD S. CODY.
